UNITED STATES PATENT OFFICE.

SAMUEL J. RAWLINGS, OF KEARNEY, NEW JERSEY.

AUTOMATIC DOOR-CHECK.

SPECIFICATION forming part of Letters Patent No. 759,013, dated May 3, 1904.

Application filed July 27, 1903. Serial No. 167,153. (No model.)

To all whom it may concern:

Be it known that I, SAMUEL J. RAWLINGS, a citizen of the United States, residing at Kearney, in the county of Hudson and State of New Jersey, have invented certain new and useful Improvements in Automatic Door-Checks; and I do hereby declare the following to be a full, clear, and exact description of the invention, such as will enable others skilled in the art to which it appertains to make and use the same.

This invention relates to improvements in automatic door-checks.

The object of the present invention is the provision of a door-check of the type adapted automatically to secure a door in its open position without the necessity of manually operating the check to cause its engagement with the door.

A further object of the invention is to provide an automatic door-check of the type mentioned which is extremely simple in construction, easy of operation, inexpensive in manufacture, and one entirely free from springs and other structural elements liable to frequent breakage and necessary repairs.

With these general objects in view and others which will appear as the nature of the improvements is better understood the invention consists, substantially, in the novel construction, combination, and arrangement of parts, as will be hereinafter fully described, illustrated in the accompanying drawings, and pointed out in the appended claims.

While the form of the invention herein shown and described is believed to be a preferable embodiment thereof, it will of course be understood that the same is susceptible of various changes in the form, proportion, and minor details of construction, and the right is therefore reserved to modify or vary the invention as falls within the spirit and scope thereof.

In the drawings, Figure 1 is a perspective view of a portion of a door and wall with a check applied thereto constructed in accordance with the present invention. Fig. 2 is a longitudinal sectional view of a check with the parts thereof engaged. Fig. 3 is a front elevation of the catch. Fig. 4 is a similar view

of the latch. Fig. 5 is a top plan view of the latter. Fig. 6 is a similar view of another form of latch. Fig. 7 is a side elevation of the latch shown in Fig. 6.

Referring to the drawings, the numeral 1 designates a catch which comprises an attaching-plate 2, the ends of which are perforated, as at 3, for the reception of screws 4 or their equivalent, to secure the plate 2 in applied position to a door, and projecting from the plate 2 at right angles to the latter and at substantially its middle portion is a tongue 5, the outer end of which terminates in a hook 6, between which latter and the plate 2 is formed a notch or recess 7. It will be observed that the outer face of the hook 6 is inclined and that the notch or recess 7 is likewise inclined and in parallelism with the inclination of the outer face of the hook 6, and consequently the edge of the notch or recess 7 nearest the plate 2 forms an inclined plane.

The numeral 8 designates a socket having outwardly extending perforated wings 9, through the perforations of which screws 10 or their equivalent are passed to secure the socket 8 to a wall or similar surface, and said socket is provided with a series of forwardly-extending braces or shields 11, the edges of which extend forwardly and downwardly and terminate at a point removed from the front edge of the bottom of the socket. Pivotedly connected, as by means of a pin 12, between the braces 11 is a latch 13, the latter being provided with a neck 14, through which the pin 12 passes, and said latch 13 is provided at its forward end with an opening 15 to receive the hook 6 of the catch. It will be observed that the inner edge of the forward end of the opening 15 is provided with oppositely-beveled faces, the lower face 16 of which conforms to the inclination of the upper end of the hook 6, while the upper face 17 is of substantially the same inclination as the inner edge of the hook 6 for a purpose to be presently stated. Depending from the lower face 16 of the latch 13 is a lug 18, which lug is designed to abut against the inner portion of the socket 8, and thus limit downward movement of said latch.

In Figs. 6 and 7 is shown a modified form

of the latch, and referring thereto it will be observed that this form is substantially the same as that disclosed in the other figures, excepting that the perforated ears 9 are attached 5 to the bottom of said socket in order to adapt the latter for application to a floor. With this form of latch it is obvious that the same may be applied at any point on a floor within the path of movement of a door and is effective for use with the latch for holding the door 10 in open position.

In practice the catch 1 is applied to a door, as illustrated in Fig. 1, and the latch is applied to the wall, as also illustrated in Fig. 1, 15 or in lieu thereof said latch may be applied to the floor by adopting the form shown in Figs. 6 and 7. When the door is swung open, the inclined front edge of the hook 6 contacts with the end of the latch 13, and the latter is 20 caused to ascend said inclined front face until the upper end of the hook 6 is at a point beneath the opening 15, when the latch 13 will gravitate so that the front end thereof will drop into the notch or recess 7, the opening 25 15 receiving the upper end of the hook 6. In this position it is obvious that the door will be prevented closing by reason of the engagement of the latch and the hook. When, however, it is desired to close the door, the latter 30 is given a quick movement first in the direction toward the socket 8 and then in the opposite direction to remove the hook 6 from beneath the opening 15 of the latch 13. In the first movement the inclined front face of 35 the hook 6 will cause the latch 13 to be elevated, so as to carry the front end thereof out of the plane of movement of the hook 6, and in the second movement, which it must be remembered is a quick one, the inclined upper 40 end of the notch 6 will contact with the lower beveled face 16 of the front end of said latch, and consequently as the upper end of the hook 6 and said beveled face are of the same inclination the end of the latch will be 45 caused to ride upon the inclined end of the hook, thus preventing engagement of the latter with the opening 15, and the catch is thus freed from the latch to permit the door being closed. In opening the door it will

also be seen that after the latch 13 is brought 50 into engagement with the hook 6 the inclined inner face of said hook will ride upon the upper beveled face 16 of the latch, and thereby cause the latch to descend into the notch or recess 7 in any slow movement of the door 55 toward the frame of the latter.

Having thus described the invention, what is claimed as new, and desired to be secured by Letters Patent, is—

1. In an automatic door-check, the combination with a catch comprising an attaching-plate, a tongue projecting therefrom, and an inclined hook carried by said tongue, the latter being provided with a notch or recess between said hook and said plate, of a socket, a latch pivoted therein and provided with a depending lug for limiting downward movement of said latch, said latch being provided with an opening adapted to receive said hook, the inner edge of the forward end of said opening being provided with oppositely-beveled faces adapted to be engaged by the inner face and end of said hook, the forward end of said latch being received by the notch of said tongue when said parts are engaged. 75

2. In an automatic door-check, the combination with a catch comprising an attaching-plate, a tongue projecting therefrom, and an inclined hook carried by said tongue, the latter being provided with a notch or recess between said hook and said plate, of a socket provided with forwardly-extending braces or shields, and a latch pivoted between said braces or shields, said latch being provided with an opening adapted to receive said hook, 80 the inner edge of the forward end of said opening being provided with oppositely-beveled faces adapted to be engaged by the inner face and end of said hook, the forward end of said latch being received by the notch of 85 said tongue when said parts are engaged.

In testimony whereof I affix my signature in the presence of two witnesses.

SAMUEL J. RAWLINGS.
